UNITED STATES PATENT OFFICE.

JOHN R. MITCHELL, OF EVANSTON, ILLINOIS, ASSIGNOR TO WILLIAM H. MINER, OF CHAZY, NEW YORK.

SLIDING-DOOR CHECK,

1,357,244.

Specification of Letters Patent. Patented Nov. 2, 1920.

Application filed May 3, 1919. Serial No. 294,445.

To all whom it may concern:

Be it known that I, JOHN R. MITCHELL, a citizen of the United States, residing at Evanston, in the county of Cook and State 5 of Illinois, have invented a certain new and useful Improvement in Sliding-Door Checks, of which the following is a full, clear, concise, and exact description; reference being had to the accompanying drawings, forming a part of this specification.

This invention relates to improvements in sliding door checks.

In the operation of railroad baggage cars, the baggagemen have frequently been injured while standing in the doorway due to the sudden closing of the heavy sliding side doors caused by sudden changes in the speed of the train. Various attempts have been made to overcome this difficulty but 20 the same have not been entirely successful, so far as I am aware.

The object of my invention is to provide a relatively inexpensive and simple arrangement that may be attached to the sliding 25 side doors of baggage cars for the purpose of effectively breaking or chocking the same against sudden and unrestricted movement to closed position to thereby avoid all possible injury to persons standing in the door- 30 way.

In the drawing forming a part of this specification, Figure 1 is an interior elevational view of a portion of a baggage car showing my improvements in connection 35 with the sliding side door thereof, the floor being shown in section. Fig. 2 is a vertical, sectional view taken substantially on the line 2—2 of Fig. 1. Fig. 3 is an enlarged, detailed sectional view taken substantially on 40 the line 3—3 of Fig. 2. And Fig. 4 is an enlarged, detail, sectional view taken substantially on the line 4—4 of Fig. 3.

In said drawing, 10 denotes a sliding side door of a baggage car such as are now in 45 common use. Said door 10 is supported by brackets 11—11 that carry anti-friction rollers 12, said rollers 12 having grooved peripheries and traveling on a horizontal rail or track 13 secured to the inner wall of the 50 car above the door opening. The door opening is defined by a suitable door framework comprising a lintel 14, side door posts 15 and threshold 16. The latter may be protected by a suitable wear plate 17 to minimize injury to the car from trucking and

the like. The wear plate 17 may be provided with an upstanding relatively shallow rib 18 engaging a corresponding groove 19 in the bottom edge of the door 10 to thereby prevent the door from swinging inwardly. 60

The door 10 is shown in Fig. 1 in its closed normal position and it will be noted that there is a slight clearance indicated at 20 in Fig. 2 between the top edge of the door and the rail support and a corresponding 65 slight clearance indicated at 21 between the bottom edge of the door and the threshold proper. From the foregoing, it will be evident that the weight of the door is carried normally by the rollers 12 mounted on the 70 track 13 and that the door 10 is relatively free to move horizontally.

In order to check sudden movements of the door toward closed position, I provide the 75 following means: Secured to the door 10 at the bottom thereof near the forward or advance edge of the door is a housing 22 preferably in the form of a casting. Said housing 22 has a flange 23 by which it may be screwed to the door and has a chamber 24 80 open at the bottom in a plane flush with the lower edge of the door. The housing 22 is preferably so constructed as to provide a vertical wall 25 at the forward end thereof, a horizontal top wall 26, a rear vertical wall 85 27, the walls 27 and 26 being connected by a curved section 28 as clearly shown in Fig. 3. Mounted within the housing 22 is a roller 29 which is loose and normally entirely free from weight of the door. Said roller 29 is 90 adapted to roll upon the floor or threshold of the car as clearly apparent from Figs. 1 and 3. Also, mounted within the housing 22 and in advance of the roller 29, that is, between the roller 29 and the forward edge of the 95 door, is a chocking block or wedge 30 having a lower horizontal face 31 and inclined wedging face 32, the latter being in proximity to the periphery of the roller 29. The chocking block 30 is made of such length that a slight amount of movement, horizontally, is 100 permissible between the vertical wall 25 of the housing and the roller 29. As shown in Fig. 3, this clearance is between the inclined surface 32 and the periphery of the roller. The chocking block 30 is adapted normally to track along the floor or threshold, and it is evident that when the door 10 is moving toward closed position, the weight of the block 30 will be sufficient to create friction 105

110

between the block and the floor and retard the block until it engages under the roller 29. Continued movement of the door toward closed position will force the roller 29 up 5 the inclined face 32, since the roller is pushed by the housing. As the roller 29 rides up the inclined face 32 of the chocking block, it is evident that the roller itself will be forced up into engagement with the top wall 26 of 10 the housing and gradually lift the door, or at least the forward portion thereof, until the upper edge of the door engages with the rail support, thus jamming the door between the rail support and the floor or threshold. Any 15 continued movement of the door toward closed position after this condition has occurred merely serves to jam the door more tightly and place more weight or pressure on the roller 29 and chocking block to thereby 20 augment the friction. In this manner, it is evident that the door cannot move freely toward closed position without becoming jammed or wedged so as to effectively stop it after a very slight movement or impulse of 25 the door toward closed position, regardless of the position in which the door is at the time it is started toward its closed position. Movement of the door 10 in an opening direction is, of course, not checked by the block 30 and roller 29 since the block will track 30 behind the roller and cannot wedge it against the housing 22.

In order to permit closing movement of the door, under control, I provide a lifting rod 33 which passes through a suitable opening 34 in the top of the housing 22 and which is pivotally connected at its lower end by means of a pin 35 to the chocking block 30. At its upper end, the rod 33 is formed with 40 a loop 36 having an elongated opening 37 therein to accommodate a suitable pin or rivet 38 rigidly carried by a lever 39 having an operating lever handle 40. The lever 39 seats loosely within a bracket 41 secured to 45 the door and it is obvious that if the handle 40 is oscillated in either direction from its vertical position, the lever 39 will fulcrum about either of its ends on the flanges 42 of the bracket 41 and thereby cause the rod 33 to be elevated. Elevation of the rod 33 will 50 obviously lift the wide end of the chocking block 30 and pull the block 30 from underneath the roller 29 sufficiently to disrupt the wedging or chocking action. The operator 55 or baggageman can move the door to its closed position by means of said handle 40 and while the chocking block is lifted as above described, the sharp end thereof will merely drag along the floor or threshold 60 without wedging against the roller 29. As will be evident, the weight of the rod 33 augments the weight of the block 30 in holding the block 30 on the floor or threshold.

The arrangement which I have provided 65 is not only simple and effective but is com-

pact and may be applied to new baggage cars as well as to those now in service. Furthermore, on account of the compactness of the arrangement, it may be placed sufficiently near the forward or advance edge of the door 70 as to permit the latter to be moved in an opening direction the necessary amount without danger of the chocking device interfering with any slats or other casing within which baggage doors usually slide as they 75 are opened.

Although I have herein shown and described what I now consider the preferred manner of carrying out the invention, the same is merely illustrative and I contemplate all changes and modifications that come within the scope of the claims appended hereto.

I claim:

1. In a check for a horizontally slidable door supported from a door framework, the check being adapted to normally prevent movement of the door toward closed position, the combination with an element movable but loosely associated with the door and normally free from any weight of the door, of a wedge member in proximity to said element and also loosely associated with the door and normally free from any weight of the door, said member being adapted to move with the door and track along an adjacent part of the door framework, said wedge member, when frictionally retarded, engaging said element and adapted to elevate the latter until both element and member support a part of the weight of the door and thereby prevent continued movement of the door toward closed position.

2. In a check for a horizontally slidable door supported from a door framework, the check being adapted to normally prevent movement of the door toward closed position, the combination with an element movable but loosely associated with the door and normally free from any weight of the door, of a wedge member in proximity to said element and also loosely associated with the door and normally free from any weight of the door, said member being adapted to move with the door and track along an adjacent part of the door framework, said wedge member, when frictionally retarded, engaging said element and adapted to elevate the latter until both element and member support a part of the weight of the door and thereby prevent continued movement of the door toward closed position, and means for manually disengaging said wedge member from operative relation with said element.

3. In a check for a horizontally slidable door supported from a door framework, the check being adapted to normally prevent movement of the door toward closed position, the combination with a roller movable 125

with but loosely associated with the door and normally free from any weight thereof, of a chocking block located in proximity to said roller and on the side thereof nearest 5 the advance edge of the door, said chocking block being also loosely associated with the door and adapted to track over an adjacent portion of the framework when the door moves toward closed position, said chocking 10 block being arranged to be frictionally retarded and to chock said roller until the roller and chocking block sustain a part of the weight of the door.

4. In a check for a horizontally slidable 15 door supported from a door framework, the check being adapted to normally prevent movement of the door toward closed position, the combination with a roller movable with but loosely associated with the door 20 and normally free from any weight thereof, of a chocking block located in proximity to said roller and on the side thereof nearest the advance edge of the door, said chocking block being also loosely associated with the door 25 and adapted to track over an adjacent portion of the framework when the door moves toward closed position, said chocking block being arranged to be frictionally retarded and to chock said roller until the roller and 30 chocking block sustain a part of the weight

of the door, and means for manually moving the chocking block to an inoperative position with respect to the roller.

5. In a check for a horizontally slidable door supported from a door framework, the 35 check being adapted to normally prevent movement of the door toward closed position, the combination with a housing carried by the door at its bottom edge, of a roller loosely mounted within said casing 40 and adapted normally to roll upon the floor, and a chocking block also loosely mounted within said housing and normally riding freely upon the floor, said chocking block being disposed on the side of the roller nearest the forward edge of the door, said chocking 45 block being arranged to track upon the floor and wedge beneath the roller when the door moves toward closed position to thereby lift the roller until it engages the housing and in turn lifts the door, a lift rod pivotally attached to the chocking block, and a manually operable lever associated with the lift rod for elevating the latter so as to lift the chocking block to an inoperative 50 position.

In witness that I claim the foregoing I have hereunto subscribed my name this 15th day of Apr., 1919.

JOHN R. MITCHELL.
